CLAIM

The ornamental design for a nail curing lamp as shown and described.

DESCRIPTION

FIG. 1 is a front, right and bottom perspective view of a nail curing lamp, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged detail view taken from area 9 of FIG. 1;

FIG. 10 is an enlarged detail view taken from area 10 of FIG. 5;

FIG. 11 is an enlarged detail view taken from area 11 of FIG. 7;

FIG. 12 is an enlarged detail view taken from area 12 of FIG. 8; and,

FIG. 13 is an enlarged detail view taken from area 13 of FIG. 8.

The evenly spaced broken lines in the figures depict portions of the nail curing lamp that form no part of the claimed design. The dot-dash broken lines define the boundaries of the enlarged detail views and form no part of the claimed design.
